DESIGN FOR A BATTERY CONNECTOR TERMINAL

Wilbur J. Padgett, New Lexington, Ohio

Application March 27, 1941, Serial No. 99,932

Term of patent 7 years

To all whom it may concern:

Be it known that I, Wilbur J. Padgett, a citizen of the United States, residing at New Lexington, in the county of Perry and State of Ohio, have invented a new, original, and ornamental Design for a Battery Connector Terminal, of which the following is a specification, reference being had to the accompanying drawing, forming part thereof.

Figure 1 is a top plan view of a battery connector terminal showing my new design.

Figure 2 is a bottom plan view thereof.

Figure 3 is a side elevational view thereof.

Figure 4 is an elevational view of the battery connector terminal, as viewed from the cable connection end.

Figure 5 is an elevational view of the battery connector terminal and viewing the same from the side thereof opposite to that shown in Figure 4.

I claim:

The ornamental design for a battery connector terminal, as shown.

WILBUR J. PADGETT.
